UNITED STATES PATENT OFFICE

HARRY GREENBAUM, OF KANSAS CITY, MISSOURI

DESIGN FOR AN OUTER DRESS GARMENT FOR LADIES' WEAR

Application filed May 23, 1930. Serial No. 35,732. Term of patent 3½ years.

To all whom it may concern:

Be it known that I, HARRY GREENBAUM, a citizen of the United States, residing at Kansas City, county of Jackson, State of Missouri, have invented a new, original, and ornamental Design for Outer Dress Garment for Ladies' Wear, of which the following is a specification, reference being had to the accompanying drawing, forming a part thereof.

In the drawing:

I claim:

The ornamental design for an outer dress garment for ladies' wear as shown.

HARRY GREENBAUM.
